UNITED STATES PATENT OFFICE.

WALTER P. SCOFIELD, OF TAMPA, FLORIDA, ASSIGNOR OF ONE-FOURTH TO D. C. GILLETT, OF CHARLESTON, SOUTH CAROLINA, AND ONE-FOURTH TO M. E. GILLETT, OF TAMPA, FLORIDA.

CAR-STANCHION.

No. 927,288.

Specification of Letters Patent.

Patented July 6, 1909.

Application filed August 10, 1908. Serial No. 447,816.

To all whom it may concern:

Be it known that I, WALTER P. SCOFIELD, a citizen of the United States, residing at Tampa, in the county of Hillsboro and State 5 of Florida, have invented certain new and useful Improvements in Car-Stanchions; and I do hereby declare the following to be a full, clear, and exact description of the invention, such as will enable others skilled in the art 10 to which it appertains to make and use the same.

My invention relates to improvements in car stanchions, and the object of my invention is to provide a car stanchion for flat 15 cars which can be adjusted and locked in a vertical position or, when desired, can be folded down and supported on the side of the car.

With this object in view, my invention 20 consists in the construction and combinations of parts as hereinafter described and claimed.

In the accompanying drawings—Figure 1 25 is a perspective view of the side beam of a flat car, showing the stanchion locked in a vertical position. Fig. 2 is a side view on an enlarged scale of a portion of the same. Fig. 3 is a side view of the same, showing the stanchion folded down at the side of the car. Fig. 4 is a longitudinal vertical section 30 through the side of the car, showing in elevation the stanchion and means for locking the same. Fig. 5 is a horizontal section of the same on the line 5—5 of Fig. 4. Fig. 6 35 is a view of the locking means detached, parts being shown in dotted lines, and Fig. 7 shows one of the stanchions let down.

a represents one of the side beams of a car, usually made of wood and countersunk for 40 the reception of the iron plate *b*, which is shouldered as shown at *c*, and held in place by the bolts *d* and by the bent rod *e*, which passes around the upper part of the plate *b*, and is secured by bolts on the inside of the beam *a*. This plate is slotted at two places, as shown at *f* and *g*, and in the recesses 45 thereby left, are pivoted two swinging arms *h* and *i* on a rod *g*, each of said arms hav-

ing on the outside a downwardly turned square projection *j*, for locking the stanchion 50 in an upright position, as hereinafter described. The part *b* is cut away at its lower central portion, as shown at *x*, for a purpose hereinafter described.

The stanchion is composed of a central 55 web *k*, and side webs *m* and *n* at right angles thereto, the whole forming substantially a T-beam, preferably made of metal. To the top of the stanchion is attached a chain *o*, which passes across to a stanchion on the 60 other side of the car, and the stanchion is provided with an eyelet *p*, through which the chain may pass. The lower part of the beam *k* is cut away as shown at *r* in the form of a 65 rectangular slot, said slot being extended on the outer side as shown at *s* for the reception of the stout rod *t*, on which the stanchion 70 is mounted, the inner ends being secured therein by nuts *u*, shown in dotted lines in Fig. 4. On each side of the web *k*, is mounted an inclined cross piece *v*, and the flanges *m* and *n* are cut away just above these inclines, leaving a space in which the arms *h* and *i* may work. The lower part of the 75 inside of the beam *k* is rounded as shown at *w*, and adapted to fit into the depression *x* on the lower part of the plate *a*.

The stanchion is provided with locking means which coöperate with the arms *h* and *i*, shown detached in Fig. 6. It consists of a 80 heavy bar *y*, to which are firmly attached upwardly projecting curved arms *z* and *1*, each terminating in an eye such as *2*, which are pivotally mounted on pins such as shown at *3* in dotted lines in Fig. 4 in the plate *m*. 85 This plate is slotted as shown at *4* and *5* in Fig. 1. To each of the arms *z* and *1*, is pivoted the end of a bell crank lever, such as *6* and *7*, each of these levers terminating at its lower point at a double eye *8*, and these eyes 90 are pivoted on a rod *9*, passing through perforations located near the center of the bent arms *z* and *1*. The upper end of the arm *7* is pivotally connected, as shown at *10*, to a 95 swinging arm having an enlargement *11*, which arm is pivoted by means of a pin pass-

ing through the hole 12, said pin being located in the slot 5, the construction being symmetrical on each side of the plate *m*, and the whole forming a toggle arrangement.

5 The stanchion is adapted to fold down, as shown in Fig. 3, and the side beam *a* is provided with a wire 13, bent at right angles, as shown in Fig. 1, and with a cam-shaped projection 14, against which the upper end of 10 the stanchion is adapted to bear when it is folded down.

Firmly attached to the plate *b* and at right angles thereto, are guide plates 15 and 16, between which the stanchion is adapted to 15 move, and which also serve as guides for the arms *h* and *i*. Each of these guide plates is provided with a triangular depression in which pins 17 and 18 on the arms *i* and *h* are adapted to engage.

20 The operation is as follows: The parts being in the position shown in Fig. 3 in which case the stanchion is in its inoperative position, the chain carrying end of the stanchion is lifted until the part *m* has been raised 25 above the top of the rod 13, the other end of the stanchion dropping meantime. The stanchion is then swung around until it is between the guide plates 15 and 16. The stanchion being still in a horizontal position, 30 it is lifted up and pushed in until the cut-away *s* engages the rod *t*. The stanchion is then swung upwardly, the part *w* engaging the groove *x*, with the arms *h* and *i* riding up on the inclines *v*. The bar *y* is then lifted 35 and the stanchion pressed in until it strikes the side of the car, the hooked ends of the arms *h* and *i* then dropping down outside of the plate *m*, and the bar *y* then falling to its 40 original position, as shown in Fig. 1, firmly locking the stanchion in an upright position.

To swing this stanchion into an inoperative position, the cycle of operations is reversed, the stanchion assuming the position shown in Fig. 3 with its upper end resting 45 against the cam piece 14, which together with the rods *t* and 13, holds the stanchion firmly in place and prevents jarring.

As shown in Fig. 7 the stanchions may be let down with their lower ends on the ground, 50 in which position they may be used as skids in loading and unloading.

I claim:—

1. The combination with a car body, of stanchions supported thereon and adapted to 55 be swung down until the lower ends thereof strike the ground, and also to be swung into a position parallel to the car body, and means for locking said stanchions in a horizontal position against said car body, and also in a 60 vertical position, substantially as described.

2. The combination of a car body and stanchions adjustably mounted thereon, and means for locking said stanchions in a verti-

cal position, said means including swinging arms mounted on the car body, and devices 65 movably mounted on the stanchion for engaging said arms and locking the stanchion firmly against the car body, substantially as described.

3. The combination of a car body, headed arms pivotally mounted thereon, stanchions adjustably mounted on said car body, and provided with means for locking said arms in engagement with said stanchions, said means including a swinging bar and a toggle 75 arrangement operated by said bar, substantially as described.

4. The combination of a car body having a supporting rod fastened thereto, and also provided with swinging, headed arms, a stanchion slotted at its lower end and mounted on said rod, said stanchion being provided with toggle locking means for engaging said arms and securing said stanchion in an upright position against the side of the car, substantially as described.

5. The combination of a car body provided with a U-shaped supporting rod and with swinging, headed arms, a stanchion slotted near its lower end and mounted upon said 90 rod, and locking means carried by said stanchion and adapted to engage said arms, consisting of a pivotally mounted bar and toggle devices connected to said bar and adapted to engage said headed arms and lock the stanchion to the side of the car, substantially as described.

6. The combination of a car body provided with a supporting rod and having headed arms pivotally attached to said body, a car 100 stanchion slotted near its lower end and engaging said rod, said stanchion being provided with inclines adapted to engage said arms as said stanchion is swung upwardly, and locking means carried by said stanchion, 105 consisting of a pivotally mounted bar and toggle devices operated by the movement of said bar, and adapted to engage said arms and lock the heads thereof against the side of the stanchion, substantially as described.

7. The combination of a car body, a supporting plate fastened to said body, and provided with projecting guide plates, a supporting rod secured to said body near the lower end of said plate, a stanchion slotted near its 115 lower end, and mounted upon said rod and adapted to swing between said guide plates, said stanchion being provided with inclines near its lower end, swinging, headed arms mounted in said plate and adapted to engage said inclines, and means for locking said headed arms against the side of said stanchion, consisting of a swinging bar pivotally mounted on said stanchion, brackets carried by said bar by means of which it is pivotally 120 supported, bent levers pivotally mounted on

said brackets, and swinging devices pivoted to said levers adapted to engage said arms, substantially as described.

8. The combination of a car body provided with bent supporting rods and a cam-shaped plate, with a stanchion slotted near one end thereof, and engaging one of said rods, the other end of said stanchion being adapted to be confined between the other of said rods and the car body, whereby said stanchion

may be firmly secured to the car body in a horizontal position, substantially as described.

In testimony whereof, I affix my signature, in presence of two witnesses.

WALTER P. SCOFIELD.
